UNITED STATES PATENT OFFICE.

DAVID STEWART, OF BESSEMER, ALABAMA, ASSIGNOR OF ONE-FOURTH TO HOWARD LAMAR, OF BIRMINGHAM, ALABAMA, AND ONE-FOURTH TO THEODORE LAMAR AND ONE-FOURTH TO N. J. STUART, BOTH OF BESSEMER, ALABAMA.

CRANKING DEVICE.

1,134,974.

Specification of Letters Patent.

Patented Apr. 6, 1915.

Application filed January 26, 1914. Serial No. 814,478.

To all whom it may concern:

Be it known that I, DAVID STEWART, a citizen of the United States, residing at Bessemer, in the county of Jefferson and 5 State of Alabama, have invented certain new and useful Improvements in Cranking Devices, of which the following is a specification.

My invention relates to safety cranking devices for explosive engines, especially 10 automobile engines.

My object is to provide a device of this character, so constructed that the sudden reversal of the engine from a premature explosion therein during the cranking operation, cannot impart a backward rotation 15 to the crank.

Another object is to provide a device of this character so constructed that however 20 suddenly or powerfully the engine to which it is attached may be reversed, there will be no strain imposed upon any part of the device.

Another object is to provide a device so 25 simple in its construction, and so sure in its operation that it can be absolutely relied upon at all times.

A still further object is to provide a device of so few parts, and of such easy and 30 cheap construction that the additional cost of attaching it to an automobile at the factory will be inappreciable; and that an average mechanic can, with his ordinary tools and facilities, apply it to any auto- 35 mobile.

Minor objects will appear in the subjoined description.

The invention consists in certain novel constructions and combinations of parts 40 hereinafter described and claimed, reference being made to the accompanying drawings.

An important feature of my invention consists in dividing the crank shaft into two sections longitudinally movable to or from each 45 other and each capable of independent rotation; and in providing these two sections of the shaft with a ratchet clutch composed of two members having coöperating ratchet faces, one member of the clutch being rigidly secured to each section of the shaft; the 50 ratchet face of one section of the clutch being of greater diameter than the coöperating face of the other section of the clutch; and a pawl adapted to ride up over the pro-

jecting teeth of the one section of the clutch 55 when the shaft is turned forwardly, and to engage said teeth and separate the two sections of the clutch when it is attempted to turn the shaft backwardly.

Referring to the drawings, Figure 1 is a 60 perspective view of my device detached from the engine. Fig. 2 is a top plan view of the clutch mechanism with the adjacent parts broken away. Fig. 3 is a longitudinal central section of the clutch and shaft mechanism, with the position of the supporting frame shown in dotted lines; and Fig. 4 is a perspective of the pawl employed for separating the two members of the clutch.

The numeral 1 indicates a suitable supporting frame, provided with openings 2 for securing the device to the automobile. The frame is also provided with the bores 3 and 4 at its inner and outer ends respectively, into which bores are received the two 75 respective sections 5 and 6 of the divided shaft. The section 6 of the divided shaft is provided at its outer end with a squared section 7 for receiving a suitable crank, and at its inner end with a central longitudinal 80 bore 8 into which is loosely received the outer end of the other section of the shaft. The section 9 of the ratchet clutch is integrally secured to the section 6 of the shaft at its inner end, and the coöperating section 10 of 85 the clutch is rigidly secured to the other section (5) of the shaft by means of the pin 11 which passes through registering bores 12 and 13 in said clutch section 10 and shaft section 5.

The collar 14 is rigidly secured to the shaft section 5 just outside the frame 1 by means of the set screw 15; and the collar 16 fills the space between the inside of the frame and the clutch section 10, by which means 95 the shaft section 5 carrying the clutch section 10 is held against longitudinal movement in the frame 1. But the outer shaft section 6 has its bore 8 of sufficient depth and its clutch section 9 sufficiently spaced 100 inwardly from the inner face of the forward end of the frame 1 to permit said section 6 to have a limited longitudinal movement on said frame, whereby to permit the clutch section 9 to be moved into and out of engagement with its coöperating clutch section 10 on the other section of the divided shaft. In order to give ample bearing to

the outer section 6 of the divided shaft, I provide the collar 17 which has the integral flange 18, by means of which it is rigidly secured to the outer forward end of the frame 1 by the bolts 19.

The clutch members 9 and 10 are provided on their inner faces with coöperating ratchet teeth 20 and 21 respectively, so that when the outer end 6 of the divided shaft is thrust sufficiently inward, the two sections 9 and 10 are brought into engagement with each other, and if the section 6 be rotated forwardly (from left to right) the rotation thereof will be imparted to the other section, the inclination of the coöperating teeth of the two sections being arranged for rotation in this direction. It will, however, be noticed that the ratchet face of the clutch section 9 is of greater diameter than the coöperating ratchet face of the section 10, and this constitutes a very important feature of my invention, as will presently appear.

The frame 1 of my device is provided with an integral projection 22 having a suitable recess 23 in which is pivoted at its outer end the pawl 24 pressed by the spring 25. The two sections 9 and 10 of the clutch are of greater diameter than their respective ratchet faces so as to provide said sections with the annular shoulders 26 and 27 respectively. Extending inwardly from the base of the shoulder 27 of the clutch section 10, is a collar 28 on the inner edge of which the series of clutch teeth 21 are formed with a space remaining between the roots of the teeth and said shoulder. The free end of the spring-pressed ratchet 24 is easily received between the two shoulders 26 and 27 of the clutch sections 9 and 10. This ratchet 24 at its forward end on its side next the projecting ratchet teeth 20 is provided with an inclined face 29 adapted to coöperate with the inclined sides of said projecting ratchet teeth, whenever it is attempted to reverse the rotation of the clutch member 9. It will be noticed that this face 29 is so inclined as to project outwardly at its bottom so that when the clutch section 9 is turned backwardly the action of the teeth 20 upon this face will impart a downward tendency to the ratchet and thus assist the spring 25 in insuring that the end of the pawl shall not fly up out of engagement with said teeth.

When backfiring of the engine takes place and starts to turn the clutch section 9 with its shaft section 6 backward, this face 29 of the pawl 24, engages the first one of the projecting teeth 20 that reaches it and instantly shunts the clutch section 9 out of engagement with its coöperating section 10, and thus prevents a backward rotation of the shaft section 6 which carries the operating crank. This leaves the section 5 of the shaft with its clutch section 10 free to con-

tinue its backward rotation without interference.

In order to increase the downward tendency of the free end of the pawl 24 when its inclined face 29 is engaged by the projecting teeth 20 of the clutch section 9, I have provided the radial edges of said teeth with a slight inward inclination from their outer ends to their inner ends and in order to make the coöperating teeth 21 of the section 10 correspond to these, their inner edges are correspondingly inclined outwardly from their outer ends to their inner ends; that is to say, in general contour, the one ratchet face is concave and the other is correspondingly convex. During the backward rotation of the clutch section 10 the extreme forward tapered end 30 of the pawl 24 rides upon the collar 28 of said clutch section. The shoulders 26 and 27 of the two clutch sections guard the free end of the pawl against lateral movement or strain.

The projection 22 of the frame 1 carries a pin 31 which forms a positive stop for limiting the upward movement of the pawl 24, to prevent the free end of the pawl from rising upwardly beyond the shoulders 26 and 27 of the clutch. This keeps the pawl from ever being moved or jolted out of operative relation to the teeth 20 and will always hold it in position to reliably operate by gravity even though the spring 25 should be broken or dispensed with.

When it is attempted to reverse the rotation of clutch section 9, the forward end 30 of the pawl is simply wedged between the shoulder 27 of the clutch section 10 and the projecting teeth 20 of the section 9 as they engage it on its face 29. In this way the pawl operates with the power of a wedge to force the two sections 9 and 10 of the clutch apart out of engagement with each other. And as only comparatively slight power is actually required for this operation, the pawl does its work with great ease and promptness, and freedom from strain or jar to any of the parts. When the clutch is rotated forwardly, the free end of the pawl simply rides up over the outer peripheral ends of the projecting teeth 20 of the clutch section 9.

In operation the crank is placed on the squared end 7 of the shaft section 6, which section is then pushed inwardly as it is rotated to cause the two sections 9 and 10 of the clutch to firmly engage each other. The shaft is then rotated forwardly in the usual manner. When thus rotated the pawl 24 rides up over the outer ends of the projecting teeth 20, but if a premature explosion takes place and suddenly reverses the rotation of the shaft section 5 and its clutch section 10, the inclined face 29 of the pawl 24 engages the projecting teeth 20 and throws the section 9 of the clutch out of engagement

with the section 10, which prevents the section 5 of the shaft from imparting rotation to the outer section 6 thereof which carries the crank.

5 In view of the construction set forth, special attention is called to the fact that when the most sudden and violent reversal of the engine takes place, there is no strain placed upon any part of my device, and the
10 parts are so few and reliable that the cost of manufacture is reduced to a minimum, and under ordinary circumstances there is practically nothing to get out of order. Moreover the device is capable of being readily applied to any automobile. These features
15 of the device, taken in connection with its thoroughly satisfactory operation, give it great value from a practical point of view.

Having thus described my invention, what
20 I claim as new and desire to secure by Letters Patent is:—

1. In cranking devices for explosive engines, the combination with coöperating clutch members provided with opposing faces having radial teeth adapted to engage each other, one of said faces projecting beyond the other; of a pawl disposed at a tangent to said clutch members and adapted, when the clutch is turned in its forward direction, to ride up over the peripheral ends of the teeth of the projecting clutch member, and when it is turned in its backward direction, to engage the radial faces of the same teeth and force said clutch members
35 apart.

2. In a device of the character described, the combination with coöperating clutch members having opposing circular faces provided with radially disposed ratchet
40 teeth adapted to interlock with each other when the clutch is rotated in its forward direction, one of said interlocking ratchet faces projecting radially beyond the other, of a stationary pawl having its free end
45 resting upon the peripheral ends of said projecting ratchet teeth and adapted to ride up over said teeth when the clutch is rotated in its forward direction, and to directly engage their inclined radially disposed faces
50 and force the one clutch member out of engagement with the other when the clutch is turned backward.

3. In a device of the character described, the combination of opposing clutch members
55 having complementary ratchet faces formed on their opposing sides, one of said ratchet faces projecting radially beyond the other; the clutch member having the greater ratchet face being movable into and out of
60 engagement with the coöperating member having the smaller ratchet face, and said latter clutch member being provided with an annular shoulder of greater diameter than the ratchet face and a stationary pawl having
65 its free end resting upon the peripheral

ends of said projecting ratchet teeth and adapted to ride up over said teeth when the clutch is rotated in its forward direction, and to drop in between the inclined sides of said projecting teeth and the said annular
70 shoulder of the opposing clutch member to directly engage said projecting teeth and force the clutch members apart when the clutch is rotated backward.

4. In a device of the character described,
75 the combination of opposing circular clutch members having complementary ratchet faces formed on their opposing sides, said members being of greater diameter than their ratchet faces to provide each clutch
80 member with an annular shoulder, and one of said ratchet faces projecting radially beyond the other; a stationary pawl disposed at a tangent to the clutch and having its free end arranged to extend in between the
85 annular shoulders of the two members thereof, and of a width to be received between said shoulders, and adapted to rest upon and ride up over the peripheral ends of said projecting ratchet teeth when the clutch
90 is rotated forwardly, and to drop in between the inclined faces of said projecting teeth and the annular shoulder of the opposing clutch section when the clutch is rotated backwardly to force the clutch members out
95 of engagement with each other; an annular bearing on said opposing clutch member to limit the downward movement of the free end of the pawl; and means for utilizing the action of the ratchet teeth upon the pawl
100 to impart a downward tendency thereto, to hold the same in firm and steady engagement with its bearing during the backward rotation of the clutch.

5. In a device of the character described,
105 the combination of two circular clutch members having opposing faces provided with coöperating ratchet teeth, said members also having annular shoulders of greater diameter than the clutch faces, one of said clutch
110 faces extending radially beyond the other; a stationary pawl arranged at a tangent to the clutch and having its free end arranged to extend in between the shoulders of the clutch members to directly engage the teeth
115 of the projecting ratchet face to force said clutch members apart; and a stop for the pawl to prevent the free end thereof from moving upwardly beyond the periphery of
120 said annular shoulders of the opposing clutch members.

6. In a device of the character described,
125 the combination with a ratchet wheel having one of its faces provided with ratchet teeth and adapted to be shunted laterally, of a pawl adapted to engage the inclined faces of the ratchet teeth to shunt the wheel, said pawl being provided at its free end with a face inclined from front to rear to correspond with the inclination of the inclined
130

faces of the ratchet teeth to be engaged by it, said face being also inclined inwardly from its bottom to its top to form an acute angle with the bottom of the pawl, to cause the lower edge of said face to be the first part engaged by the inclined faces of the said ratchet teeth as they contact with it.

In testimony whereof I affix my signature in presence of two witnesses.

DAVID STEWART.
